DESIGN FOR A RIVET IRON

John W. Harrison, Mansfield, Ohio, assignor to
Westinghouse Electric & Manufacturing Com-
pany, a corporation of Pennsylvania

Application July 9, 1942, Serial No. 107,451

Term of patent 14 years

To all whom it may concern:

Be it known that I, John W. Harrison, a citizen of the United States, residing at Mansfield, in the county of Richland and State of Ohio, have invented a new, original, and ornamental Design for a Rivet Iron, of which the following is a specification, reference being had to the accompanying drawing forming part thereof, in which:

Figure 1 is a view in side elevation of a rivet iron showing my new design, the concealed side being substantially like the side shown;

Fig. 2 is a top plan view of the rivet iron; and
Fig. 3 is a view in end elevation taken from the right-hand end of Fig. 1.

The dominant features of my design reside in the portions shown in full lines.

I claim:

The ornamental design for a rivet iron, substantially as shown and described.

JOHN W. HARRISON.
